UNITED STATES PATENT OFFICE.

THOMAS JOSEPH STURTEVANT, OF WELLESLEY, MASSACHUSETTS, ASSIGNOR TO STURTEVANT MILL COMPANY, A CORPORATION OF MAINE.

SCREENING OR SEPARATING MACHINE.

1,229,814.

Specification of Letters Patent. Patented June 12, 1917.

Application filed December 30, 1916. Serial No. 139,938.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Screening or Separating Machines, of which the following is a specification, reference being had therein to the 10 accompanying drawings.

This invention relates to certain improvements in that class of inclined screening or separating machines shown in the Sturtevant Patents Nos. 1,035,262 and 15 1,114,064, and the invention has for its object to provide machines of this class which will be dust-proof and in which the screens may be percussively jarred or vibrated in such a manner as to secure an efficient 20 screening operation.

In the present improved machine the screens are suspended from the cover of the screen casing and which cover is preferably elastically mounted on a cover frame; flexible, dust-tight connections being provided 25 between the cover and its frame and the jarring mechanism being entirely outside of the cover so that no parts of said jarring mechanism need extend through the cover; thus avoiding any openings in the cover 30 through which dust might escape, all as will hereinafter more fully appear.

In the accompanying drawings Figure 1 is a partly broken out side view of an inclined separator embodying the present invention, and Fig. 2 is a cross section of the same on line 2-2, Fig. 1. Fig. 3 is a detail plan view of the cover-frame and cover with the jarring mechanism mounted thereon. Fig. 4 is a detail sectional view illustrating the construction by which the cover and cover-frame are mounted, and Fig. 5 is a detail view illustrative of the jarring mechanism.

Referring to the drawings, 12 denotes the screen casing which will preferably be of sheet steel, and which is preferably mounted in an inclined position on frame parts 13 in such a manner that its inclination 45 may be varied. Secured to the upper end of the screen casing 12 is a feed box 14 within which is a rotary screw conveyer, as in the separator of the Sturtevant patents hereinbefore referred to, said screw conveyer be-

ing carried by a shaft 15 provided at one 55 end with a driving pulley 16, and at its opposite end with a pulley 17. The pulley 17 is belted to a pulley 18 on a shaft 19 having bearings in standards 20 attached to the frame 21 of a cover 22 for the said casing 12, said shaft 19 being provided with a pulley 23 belted to a similar pulley 24 on a second shaft 19, also having bearings in standards 20 attached to the cover frame 21.

The shafts 19 are provided with tappets 25 arranged to engage the shorter arms of bell-crank hammers 26 which strike at intervals on impact blocks 27 resting loosely in protecting sockets 28 mounted on the cover 22, for the purpose of percussively 70 jarring said cover and the screen or screens connected therewith. The screening member or members are suspended from said cover within the screen casing by means of side plates 29 attached at their tops to said 75 cover by means of angle bars 30. The side plates 29 are preferably provided with inwardly extending flanges 31 afforded by angle bars attached to said cover, said flanges serving as supports for the side frame parts 80 32 of a coarse or scalper screen 33.

Attached to the lower parts of said side plates 29 are angle bars 34 to which is attached, in any suitable manner, the screen clothing 35 of the fine wire mesh screen. 85 Dust-tight joints between the cover 22 and the cover-frame 21 are provided by means of flexible connections 36, which may be of strong canvas or other suitable dust-tight flexible material, so that no dust can escape 90 at the joints between the vibrating cover and its stationary frame resting on the casing 12. The cover 22 is preferably resiliently supported from the cover-frame 21 by means of springs 37 attached to said 95 cover, as more clearly shown in detail in Fig. 4, and bearing at their free ends on the said cover-frame. The cover-frame is provided at its upper end with arms 38 which are jointed at 39 to similar arms 40 100 mounted on a fixed part of the casing 12, so that the said cover-frame and cover may be lifted on the hinge afforded by the joints 39, when access to the screen or the chamber of the screen casing is desired.

From the foregoing it will be apparent that when the machine is in operation the resiliently mounted cover 22 and the screens

supported therefrom will be percussively jarred, in an efficient manner, by mechanism which is entirely outside of the screen casing which is provided with a dust-tight cover, so that dust cannot escape from the top of said screen casing when the machine is in operation.

The invention is not to be understood to be limited to the details of construction herein shown and described, as such details may be varied widely, within the province of mechanical skill, without departing from the scope of the invention as defined by the claims hereunto appended.

Having thus described my invention I claim and desire to secure by Letters Patent:

1. In a separator, the combination with a screen casing and a screen or screens mounted therein, of mechanism, arranged above and entirely outside of said casing, for percussively jarring said screen or screens.

2. In a separator, the combination with an inclosing casing provided with a cover, of a screen or screens supported from said cover within said casing, and mechanism, entirely outside of said casing and above said cover, for percussively jarring said screen or screens.

3. In a separator, the combination with an inclosing casing provided with a hinged cover, of a screen or screens supported from said cover within said casing, and mechanism, entirely outside of said casing and above said cover, for percussively jarring said screen or screens.

4. In a separator, the combination with an inclosing casing provided with a cover, of a screen or screens supported by said cover within said casing, a cover-frame adapted to rest on said casing and having flexible dust-tight connections with said cover, and mechanism for percussively jarring said cover.

5. In a separator, the combination with an inclosing casing provided with a hinged cover, of a screen or screens supported by said cover within said casing, a cover-frame adapted to rest on said casing and having flexible dust-tight connections with said cover, and mechanism for percussively jarring said cover.

6. In a separator, the combination with an inclosing casing provided with a cover, of a screen or screens supported by said cover within said casing, a cover-frame adapted to rest on said casing and having flexible dust-tight connections with said cover,

means for resiliently supporting said cover on said frame, and mechanism for percussively jarring said cover.

7. In a separator, the combination with a casing provided with a cover, a cover-frame from which said cover is resiliently supported, dust-tight flexible connections between said cover and frame, a screen or screens suspended from said cover within said casing, impact devices mounted on said cover, and means, acting on said impact devices, for percussively jarring said screen or screens.

8. In a separator, the combination with a casing, of a screen or screens yieldingly supported within said casing, and means, entirely outside of said casing, for percussively jarring said screen or screens through an imperforate part.

9. In a separator, the combination with a casing provided with a cover, of a screen or screens yieldingly suspended from said cover within said casing, protecting sockets mounted on said cover, impact blocks in said sockets, hammers for percussively acting on said impact blocks, and rotating shafts provided with means for lifting said hammers at intervals.

10. In a separator, the combination with a casing provided with a hinged cover, of a screen or screens yieldingly suspended from said cover within said casing, protecting sockets mounted on said cover, impact blocks in said sockets, hammers for percussively acting on said impact blocks, and rotating shafts provided with means for lifting said hammers at intervals.

11. In a separator, the combination with a casing, of a cover-frame adapted to rest on said casing, a cover resiliently supported from said frame, impact devices supported by said cover, standards supported by said cover-frame, hammers for percussively acting on said impact devices, and rotating shafts supported by said standards and provided with means for lifting said hammers at intervals.

12. In a separator, the combination with a casing, of a cover-frame adapted to rest on said casing, a cover resiliently supported from said frame, and having dust-tight flexible connections therewith, impact devices supported by said cover, standards supported by said cover-frame, hammers for percussively acting on said impact devices, and rotating shafts supported by said standards and provided with means for lifting said hammers at intervals.

In testimony whereof I affix my signature.
THOMAS JOSEPH STURTEVANT.
